UNITED STATES PATENT OFFICE

145,101

DESIGN FOR A DOLL

Arthur D. Norcross, New York, N. Y., assignor to Norcross, New York, N. Y., a firm

Application January 3, 1945, Serial No. 117,235

Term of patent 14 years

(CL. D34—4)

To all whom it may concern:

Be it known that I, Arthur D. Norcross, a citizen of the United States, residing in the Borough of Manhattan of the city, county, and State of New York, have invented a new, original, and ornamental Design for Dolls, of which the following is a specification, reference being had to the accompanying drawings, forming part thereof.

I claim:

The ornamental design for a doll, as shown.

ARTHUR D. NORCROSS.
